Primary Examiner — Katrina A Betton*(74) Attorney, Agent, or Firm* — Botos Churchill IP Law(57) **CLAIM**

The ornamental design for an autonomous vehicle pull over button, as shown and described.

DESCRIPTION

The present application is related to application Ser. No. 29/491,937, entitled autonomous vehicle overall interior; to application Ser. No. 29/491,870, entitled autonomous vehicle storage bin/tray; to application Ser. No. 29/491,867, entitled autonomous vehicle console; to application Ser. No. 29/491,868, entitled autonomous vehicle seat; and to application Ser. No. 29/491,885, entitled autonomous vehicle control buttons, each of which is filed concurrently herewith, the entire disclosures of which are incorporated by reference herein.

The FIGURE is a top view of an image for an autonomous vehicle pull over button according to our design.

The features shown in broken lines are environmental only and form no part of the claimed design.

As shown in the figure, the autonomous vehicle pull over button is planar.
